Primary Examiner — Leanne Was-Englehart*(74) Attorney, Agent, or Firm* — Blank Rome LLP(57) CLAIM

The ornamental design for a bottle, as shown and described.

DESCRIPTION

FIG. 1 is a perspective view of a bottle showing our new design;

FIG. 2 is a front view thereof, the back view being a mirror image thereof;

FIG. 3 is a right side view thereof, the left side view being a mirror image thereof;

FIG. 4 is a top view thereof;

FIG. 5 is a bottom view thereof;

FIG. 6 is a cross-section view of the bottle taken along line 6-6 in FIG. 3; and,

FIG. 7 is a bottom perspective view thereof.

The broken lines in the Figures illustrate portions of the bottle that form no part of the claimed design.

1 Claim, 3 Drawing Sheets(56)
